SELF DISPENSING LIQUID PACKAGE

Filed May 29, 1926

UNITED STATES PATENT OFFICE

JOHN F. WERDER, OF CLEVELAND, OHIO, ASSIGNOR OF ONE-HALF TO EDMUND ROGERS

SELF-DISPENSING LIQUID PACKAGE

Application filed May 29, 1926. Serial No. 112,584.

This invention relates to a dispensing can for use with liquid under pressure of gases dissolved or absorbed therein.

It more particularly concerns a receptacle for holding and dispensing the lubricant mixture set forth in my copending application Serial No. 103,352, filed April 20, 1926, which discloses the use of a lubricant oil containing an absorbed or dissolved gas therein, which oil is maintained in storage under a substantial pressure, varying for example from 50 to 75 lbs. according to conditions of manufacture and the season of the year, and which is intended to be dispensed in a small jet under the pressure of the gas within a receptacle, which gas is maintained under such a substantial pressure by the escape of the dissolved gas from the lubricating mixture itself during the progress of the dispensing. The device is not, however, limited solely to such employment, but may be utilized in other circumstances where the storage and the dispensing of small quantities of various liquids is to be attained.

It has been found difficult in practice to construct cans of sheet metal which are capable of withstanding the pressures involved. The ends or heads of such cans must necessarily be bulged or convex to a certain extent, and yet it is difficult, if not impossible, to handle rounded or convex ends in the guideways of the usual can making machines.

I therefore propose to make and assemble the cans with flat heads or ends, so that they can readily pass through the machines, and then subject them to a forming operation for producing the necessary bulging ends. In practice, this forming operation takes place co-incidently with the testing of the finished cans for possible leakage.

The present system therefore presents the advantage of a cheaply manufactured can which is tested in the course of manufacturing, and which is capable of manufacture on the usual machine.

In the drawings:

Figure 1 represents the can partly in elevation and partly in section, showing the

can blank in full lines and the extended can in dotted lines.

Figure 2 is a vertical section through the can showing its condition when substantially filled with lubricant material.

Fig. 3 is a similar section showing the can when only a small portion of the lubricant material remains therein.

The can is formed as shown in Fig. 1 of the cylindrical side wall or body 10, the upper end wall or head 11 and the lower end wall or head 12, which are joined together by soldering or seaming, and when the can blank is assembled of these three members, it constitutes a cylinder with substantially flat ends, as the can ends themselves are recessed inwardly.

These heads are formed with ridges therein to assist in the bulging operation which is to be accomplished later. These heads are formed in the usual manner on stamping machines and the ends are placed upon the can bodies or sleeves by the usual machinery employed for that purpose, and the solder joint to secure them to the sleeve requires no particular attention above that now required in such operations. It is preferred to provide the supporting feet, hereinafter described, in the lower end of the can during the operation of forming the can end. As will be seen in Fig. 1, however, it is essential that any ridges or projections in the can ends should not extend beyond the flat plane defined by the periphery of such ends, since otherwise these projections would come in contact with the guides during the transportation of the can from one part of the assembly machine to another, and possibly result in wedging or sticking of the can in these guides.

The top head 11 of the can is preferably pierced by a suitable instrument so that the edges of the aperture thus formed are curled downwardly as shown at 13 and form a long bearing to receive the plug 14 of a fluid pressure pipe 15. It is preferred to form a tight seal between a collar 16 on this pipe and the end 11 of the can, by a suitable sealing means, preferably by forming a closed joint of easily fusible solder.

A fluid under pressure is then admitted through the pipe 15 into the interior of the can, and the pressure is increased within the body of the can until the latter is subjected to an internal pressure of, for example, 100 lbs. to the square inch. This pressure causes the ends to become bulged into the position shown in dotted lines at 11^a and 12^a in Fig. 1. This constitutes the second operation of forming the can. During this operation, which occurs at a pressure greater than that later to be employed during storage, the can is tested: and in the event of a poor joint or a poor seam, leakage or rupture will occur.

The third operation consists in mounting within the can a vertical discharge pipe 17 which extends into the can through the aperture above referred to, and projects for a distance sufficient when the pressure within the interior of the can is atmospheric, to bring its lower end substantially into contact with the bottom 12^a of the can. It is preferred to form this pipe of small metal tubing and to attach to its upper end a valve body 18. The valve is formed with a knurled operating head 20 and a screw stem 21 which has a cone 22 at its lower end adapted to seat upon and close a passage through the valve body. When this cone 22 is lifted from its seat, the contents of the pipe 17 may be discharged through a lateral nozzle 23.

The method of making this valve and its particular structure is set forth in my copending application Serial No. 124,150, filed July 22, 1926, and since this valve itself forms no part of the present invention save as a controlling means for the discharge tube, reference is made to the copending application for a disclosure of the interior structure of the valve.

In order to fit the pre-assembled pipe 17 and valve body 18 in the can, the solder connection between the pipe 15 and the can end 11^a is first loosened by the application of heat, and the can is detached from the pipe 15. The pipe 17, carrying the valve 18, is then inserted in the aperture, and forms a snug fit with the downwardly curled edges 13 thereof. It is pushed down until the valve rests upon the top of the can, as shown in Figure 2.

It will be understood that the discharge pipe 17 is inserted in and permanently secured to the lower end of the valve body, preliminary to the operation of placing the pipe within the can proper: in this way the valve body and the pipe may be handled as a unit and there is no liability of the pipe becoming separated from the valve body during the operation of assembling within the can. A little solder may now be placed at the joining edge of the valve body 18 and the can top 11^a, and a soldering iron run

around the joint to secure the valve body rigidly in place. The can is now complete.

The filling operation is next accomplished, which consists in placing the can in a suitable rack and bringing the discharge nozzle 23 of the valve into sealing contact with a feeder pipe. The mixture of lubricant and gas, under pressure, is brought into the feeder pipe, and is forced into the container through the open valve. When the entering mixture of lubricant and gas is under a pressure of 50 to 75 lbs., it is found in practice that the cans become substantially half filled with the mixture. It is preferred to have the can in an inverted position during this operation, so that the mixture passes from the valve upwardly into the discharge pipe 17 and overflows from the open end of the latter into the can. The air remaining within the can is trapped in the upper portion thereof during this first filling operation. The feeder pipe is then closed, and the can moved slightly away from the connection which is applied to the nozzle 23. The air contained in the inverted can is then discharged through the pipe 17 and the nozzle 23. During this operation very little gas will escape from the lubricant mixture, since the operation can be performed very rapidly and requires but a short time. The can is then again connected to the feeder pipe and mixture is forced in as before, and it is found in practice that about one-half of the former empty space in the can is filled before the back pressure builds up sufficiently to stop the flow. The relief of the air and gas contained above the fluid is again accomplished as before, and a further filling operation takes place. It is found in practice that in this way with four or five bleedings of the trapped air, the can is substantially filled with the mixture.

Very little of the absorbed gas is lost in this way, since this gas is more soluble in the liquid than is the air contained within the can, and the escape of a slight quantity of the gas into the air assists in rapidly scavaging away the air without an excessive loss of dissolved gas. When pressure is again placed upon the can the gas which may have collected in the can is again brought into solution in the mixture.

Another method of operation for this purpose is to previously fill the can with the gas which is employed in the mixture, and then force the mixture in under gradually increasing pressure.

When the can has been filled, the valve stem 21 is screwed down. The container is then ready for sale.

It has been found in practice that a container filled with this lubricant mixture may be kept for a very long time without loss: the pressure upon the liquid increases slightly in summer owing to the heating effect

and the lower solubility of gas in the liquid while warm, but it is redissolved again when cooled. The pressure therefore varies in a filled can between 50 to 75 lbs. in practice according to the prevailing temperatures.

When liquid under pressure is first admitted to the can to fill it, the pipe 17 is very close to the bottom 12^a of the can, but its open end is sufficiently uncovered to permit the liquid to flow into the can. After the can has been filled, the ends of the can are forced outward by reason of the high internal pressure, and assume a position such as shown with some exaggeration for clearness in Fig. 2, in which the duct 17 is held well above the bottom 12^a of the can. The liquid level is indicated by the line *a* near the top.

As the lubricant is dispensed from the nozzle from time to time, the quantity of the liquid with dissolved gas therein is decreased and thereby the pressure of the gas above the liquid in the can momentarily decreases at each discharge: since the lubricant mixture is preferably saturated with gas when the can is full, this lowering of pressure of the gas above the liquid causes a giving off of gas from the liquid itself, whereby the gaseous pressure above the liquid is restored, and is maintained in a stable equilibrium in such phase relation to the liquid solution that saturation always is present in the liquid at the particular pressure and temperature existing, and the gas maintains the whole mixture at a substantial pressure above atmospheric.

As the volume of liquid decreases, the pressure within the can likewise somewhat decreases, so that when but a few drops remain within the can the pressure has fallen to around 20 or 25 lbs. This is sufficient to still deliver the last drops to a considerable projective distance from the nozzle 23. The internal pressure, however, is no longer capable of supporting the ends of the can in the extreme bulged position shown in Fig. 2, and these ends, being of flexible and resilient sheet metal, tend to retreat to the position shown in Fig. 3, the difference being indicated by the pairs of dot-and-dash lines in these figures. As the ends move closer together, the end of pipe 17 approaches the bottom 12^a, so that finally the pipe is substantially in contact with the bottom as set forth above, and therefore capable of removing the last few drops from the lowest point of the can when the latter is held in a vertical position.

It will be understood that, for example, when a pressure of 100 lbs. is admitted into the interior of the can for bulging it, the ends will each move outward a distance of say three-sixteenths of an inch. When this pressure is released the ends, being biased inwardly, will each return about one-thirty-

second of an inch, or a total of one-sixteenth of an inch. When the lubricant mixture is forced in under a pressure of 50 to 75 lbs. the ends will again bulge outwardly a distance which is a fraction of this one-sixteenth, for example, one-thirty-second of an inch. The tube may therefore be carried one-sixteenth of an inch or more away from the bottom 12^a of the can when under the initial pressure of 50 lbs. As the pressure decreases, the can ends gradually return, so that finally the tube is substantially in contact with the bottom 12^a as aforesaid.

While it has been stated to be preferred to have the ends of the can capable of relative movement toward and away from each other, yet it is not essential that the material forming these ends should permit this yielding, since the receptacle may be satisfactorily employed when very thick sheet metal is used and no substantial change of the distance between the ends occurs as a result of the varying pressures within the can.

As above stated, it is preferred to form the small annular ridges or corrugations as shown at 25, in the heads of the cans to facilitate the bulging operation. In order to cause the can to stand firmly upon its bottom in a vertical position, the bottom end 12^a is formed with the three or more depressed knobs or feet 26 which are formed during the stamping of the bottom of the can.

This receptacle may likewise be used to store and dispense insecticides, etc., containing an absorbed gas. It presents a cheaply constructible article which may be sold with its contents as a package, and, when emptied, may be discarded.

The method of forming cans may also be employed in making cans without pipes, but such cans must be employed in an inverted position.

It is apparent that the invention is not limited to the specific form or procedure described, but that it may be modified within the scope of the appended claims.

What I claim is:

1. A pressure-liquid storage and dispensing receptacle including inwardly biased, resilient, flexible top and bottom walls and a pipe fastened to said top wall and extending within said receptacle and presenting its open lower end substantially at said bottom wall, the lower end of said pipe being supported by said top wall at varying distances from said bottom wall by the action of the pressure within the receptacle upon said flexible walls.

2. A storage and dispensing receptacle for liquids containing a dissolved gas under pressure, including top and bottom walls and a pipe sealed in said top wall and extending within said receptacle and presenting its open lower end substantially at said bottom wall, at least one of said walls being

flexible, resilient and inwardly biased, whereby said pipe is supported to present its lower end at varying distances from said bottom wall according to the pressure within in the receptacle.

3. A pressure-liquid storage and dispensing receptacle comprising side, top and bottom walls; said top wall having an aperture with downwardly curled guide edges, 10 a pipe guided by said edges and extending downwardly into said can and presenting its open lower end substantially at the bottom wall of said can, and a valve connected to the upper end of said pipe; said valve, 15 pipe and top wall being secured and sealed together.

4. A pressure-liquid storage and dispensing receptacle comprising side, top and bottom walls; a valve body having a nozzle and a closure element; a discharge pipe set in said body; said top wall having an aperture to receive said pipe, and said valve body forming a stop against said top wall to support said pipe in said can with its lower 20 end substantially at said bottom wall; and a solder securing and sealing joint between 25 said valve body, said pipe and said top wall.

5. A storage and dispensing receptacle including sheet-metal side walls and ends, one 30 of said ends having an aperture with an inwardly directed flange surrounding the same, a discharge tube projecting through said aperture and guided by said flange, a valve body mounted upon the outer surface 35 of said end and secured to said tube, and a solder sealing and supporting joint between said valve body and said end.

6. As an article of manufacture, a package 40 comprising a sheet metal can having resilient, inwardly biased convex ends, said can being filled with a liquid charged with an absorbed gas to a point where the internal pressure causes said ends to bulge outwardly, and a discharge pipe secured in said 45 top end and extending downwardly into proximity with the bottom end, whereby, as the liquid is discharged and the pressure decreases, the end of said pipe is caused to approach said bottom more and more 50 closely, so that the last remaining portion of said liquid can enter the same.

7. As an article of manufacture, a package 55 comprising a sheet metal can having flexible ends, said can being filled with a liquid charged with an absorbed gas to a point where the internal pressure causes the said ends to bulge, a discharge pipe secured in and passing through the upper end and extending downwardly into the 60 liquid, and a manually operated valve controlling the upper end of said pipe.

8. As an article of manufacture, a package 65 comprising a sheet metal can consisting of body and ends and having only crimped and soldered seams and joints, said can be-

ing filled with a liquid charged with an absorbed gas to such a degree as to produce a relatively high internal pressure, a discharge pipe extending from a point near the bottom, up through the top of said can, and a manually operated valve controlling the upper end of said pipe. 70

9. As an article of manufacture, a device for dispensing oils, comprising a hermetically sealed receptacle having a manually controlled discharge nozzle and containing an oil liquid at ordinary temperatures and pressures and saturated with a dissolved gas under pressure. 75

10. As an article of manufacture, a package 80 comprising a thin sheet metal can consisting of body and ends, and having only crimped and soldered seams and joints, said can containing a liquid charged with an absorbed gas to such a degree as to produce at normal temperatures an internal pressure of approximately fifty pounds to the square inch, a discharge nozzle communicating with the interior of the can and mounted on one of its ends, and a manually operated valve controlling said nozzle. 85

11. As an article of manufacture, a package 90 comprising a hermetically sealed sheet metal can having a manually controlled discharge opening, and containing a hydrocarbon liquid at ordinary temperatures and pressures and charged with an absorbed incombustible gas under pressure. 95

12. As an article of manufacture, a package 100 comprising a hermetically sealed sheet metal can having a top and bottom, a discharge pipe extending from a point near the bottom up through the top, and a manually operated valve controlling the upper end of said pipe, said can containing a hydrocarbon oil liquid at ordinary temperatures and pressures and charged with an absorbed neutral gas under pressure. 105

13. A storage and dispensing receptacle 110 comprising a top wall formed of sheet metal and having therein an aperture surrounded by a downwardly and inwardly extending flange, a pipe passing tightly through said aperture and engaging said flange, and means for rigidly securing said pipe to said top wall. 115

14. A storage and dispensing receptacle 120 comprising a top wall formed of sheet metal and having an aperture therein, the metal surrounding said aperture being curled downwardly and inwardly to form an annular flange on the under side of said top wall, a pipe passing through said aperture and snugly engaging said flange, and means for securing said pipe in position. 125

In testimony whereof I affix my signature.

JOHN F. WERDER.
